(57) **CLAIM**

The ornamental design for a briefcase stereo, as shown and described.

DESCRIPTION

FIG. 1 is a front perspective view.

FIG. 2 is a front elevation view.

FIG. 3 is a rear elevation view.

FIG. 4 is a side elevation view.

FIG. 5 is a side elevation view.

FIG. 6 is a top view.

FIG. 7 is a bottom view.

FIG. 8 is rear perspective view.

FIG. 9 is a front perspective view.

FIG. 10 is a front elevation view.

FIG. 11 is a rear elevation view.

FIG. 12 is a side elevation view.

FIG. 13 is a side elevation view.

FIG. 14 is a top elevation view.

FIG. 15 is a bottom elevation view.

FIG. 16 is a rear perspective view.

FIG. 17 is a front perspective view.

FIG. 18 is a front elevation view.

FIG. 19 is a rear elevation view.

FIG. 20 is a side elevation view.

FIG. 21 is a side elevation view.

FIG. 22 is a top elevation view.

FIG. 23 is bottom elevation view; and,

FIG. 24 is a rear perspective view.

The different shading techniques used depict a contrast of appearance only and does not represent a particular color, material, or texture. The broken lines in the Figures are for environment illustration purposes only.

The broken lines depict portions of the briefcase stereo that forms no part of the claimed design.

1 Claim, 18 Drawing Sheets
